SELF-DISCHARGING CAR.

1,410,154.

Specification of Letters Patent. Patented Mar. 21, 1922.

Application filed January 15, 1921. Serial No. 437,571.

To all whom it may concern:

Be it known that I, KARL BARTH, residing at Essen, Germany, a citizen of the German Republic, have invented a certain new and useful Improvement in Self-Discharging Cars, (for which I have filed an application in Germany, April 24, 1919,) of which the following is a specification.

This invention relates to self-discharging cars having a bottom adapted to tilt toward both sides. The object of the invention is to produce a spring arrangement for cars of this kind in which during the discharge movement of the bottom and entirely regardless whether the discharge be effected toward the one side or the other, always a portion of the mechanical work thereby released will be stored up in order to be utilized for the purpose of returning the said bottom into the loading position.

The invention will be further described with reference to the accompanying drawing which shows, by way of example, one embodiment of the subject matter of the invention and in which:

Fig. 1 is a diagram disclosing a cross section through the car when ready for loading.

Fig. 2 is a section through the car after a discharge toward the left, and

Fig. 3 is a section through the car after a discharge toward the right.

The arrangement of the gear elements serving to shift the bottom into the discharge position and then to return it into the loading position, does not form a feature of this invention and does not therefore require a more detailed explanation. Attention is only called to the fact, that there are arranged on the underframe A, symmetrically with respect to the middle longitudinal plane of the car crank arms B which, when the bottom C is in the loading position (Fig. 1), are capable of being fixed in a position in which they are disposed in parallel to the middle longitudinal plane and which are connected to the bottom by a link D each, disposed in the same direction, and which link is capable of only rocking outwardly, relatively to the bottom, towards the middle line of the car.

On the underframe A and this on the outside of the longitudinal girders a^1 , there are mounted bell crank levers E E^1 adapted to rock about an axis disposed in the longitudi-

nal direction of the underframe. Each of the bell crank levers is adapted to bear up with its shorter arm E against the respective longitudinal girder a^1 , whereas with its longer arm E^1 it engages the one end of a tension spring F. The opposite end of each of said tension springs F is linked to the bottom C of the car. When the car is ready for loading (Fig. 1), the springs F are tensioned to such a degree that the arms E of the bell crank levers, under the action of the springs F, will bear up with pressure against the longitudinal girders a^1 .

When the car is to be discharged toward one side, say, for example, toward the left, then the crank arms B disposed to the left of the middle longitudinal plane of the car, are turned for a slight amount inwards in the direction denoted by the arrow α in Fig.

1. Acting under the weight of the goods, the bottom C then automatically tilts toward the left and in so doing it turns about hinge connections serving to unite the right-hand crank arms B with their respective links D. As the discharging motion sets in, firstly the tension springs F arranged to the left of the middle longitudinal plane of the car relax, and as the discharging motion continues the respective bell crank levers E E^1 turn down (Fig. 2), so that the springs will now become inoperative. As Fig. 2 shows, the tension springs arranged to the right of the middle longitudinal plane of the car come to be considerably stretched during the discharging motion so that a part of the mechanical work done as the bottom passed over into the discharge position, is now stored up in the said springs.

As the bottom is to be returned into the loading position, the crank arms B located to the left of the middle longitudinal plane of the car are rotated counter to the direction indicated by the arrow α (Fig. 1) back into their initial position shown in this said figure. This return motion of the crank arms has the result that the bottom C likewise returns into its initial position, in which case mechanical work has to be accomplished which depends upon the weight conditions of the movable parts, in particular, of the bottom. In the course of the return motion of the bottom C back into the loading position, the springs F on the right-hand side relax to their original degree of

tension and in so doing they give up again the mechanical work stored up within them, so that only a slight amount of power will be required to set the crank arms B in motion, 5 this operation being effected by hand. The springs F arranged to the left of the middle longitudinal plane of the car and which during the described operation are not in tension, as also the bell crank levers E E¹ 10 connected thereto, are taken along by the bottom C as this latter returns into its original position until, as the said return movement terminates, the arms E of the bell crank levers come to bear up against the longitudinal girders ^{a1} again, whereupon the bottom C, which continues its movement yet 15 for a little space, slightly tensions the springs again.

In what manner the bottom is discharged 20 toward the right (Fig. 3) will not require any further explanation after the foregoing description, since the operations carried out are, with a suitable variation, exactly the same as when the car is discharged toward 25 the left.

I claim:

1. A dumping receptacle comprising an underframe, a tiltable bottom capable of rocking motion either way about a center, 30 spring means on either side of said bottom and connected to said bottom and to said underframe, and means for automatically releasing the spring tension on the dumping side of said bottom and increasing the tension 35 on the opposite side.

2. A dumping receptacle comprising an underframe, a tiltable bottom capable of rocking motion either way about a center, levers mounted on said underframe on either 40 side of said bottom, springs on either side of said bottom and connected to said bottom and to said levers respectively, and abutment means for said levers fixing said levers relatively to said underframe when said bot-

tom rocks back a predetermined amount on 45 its return to normal.

3. A dumping receptacle comprising an underframe, a tiltable bottom capable of rocking motion either way about a center, bell crank levers mounted on said underframe on either side of said bottom, springs connected to said bottom and to one arm of said bell-crank levers respectively, the other arms of said bell-crank levers abutting 50 against said underframe when said bottom rocks back a predetermined amount on 55 its return to normal.

4. A dumping receptacle comprising an underframe, a tiltable bottom capable of rocking motion either way about a center, 60 bell crank levers mounted on said underframe on either side of said bottom, tension springs connected to said bottom and to one arm of said bell-crank levers respectively, the other arms of said bell-crank levers abutting 65 against said underframe when said bottom rocks back a predetermined amount on its return to normal.

5. A dumping receptacle comprising an underframe, a tiltable bottom capable of 70 rocking motion either way about a center, a plurality of supporting link means on either side of said receptacle for collapsibly supporting said bottom when desired, spring means on either side of said bottom and connected to said bottom and to said underframe and means for automatically releasing 75 the spring tension on the dumping side of said bottom and increasing the tension on the opposite side. 80

The foregoing specification signed at Essen, Germany, this 15th day of November, 1920.

KARL BARTH.
